GRAB

Application filed March 11, 1931, Serial No. 521,787, and in Denmark March 11, 1930.

My invention relates to a grab with jaws, the axes of rotation of which are fixed relatively to each other in a frame, and the upper parts of which are in their closed position connected individually with a crosshead, the so-called closing crosshead, by a link, preferably a pressure bar. The crosshead is connected with the top piece for instance by pulley blocks, so that the effect of the hoisting cables to lift the crosshead is increased. The hitherto known bucket grabs of this kind are advantageous because of their small height, great gripping power and very great closing force, but they have the disadvantage of requiring particular means for procuring the vertical guiding of the closing crosshead necessary to the uniform motion of the jaws. It has been proposed to provide the frame with rigid guide-bars, but this has proved insufficient, because these guides have to project far downwards and will, therefore, be bent and quickly worn as a consequence of the outer influences to which they are exposed. Telescopic guides too have proved unfit. Moreover, the use of rigid guiding rails, or other proposed guides, as for instance toothed arcs, directly on the jaws require a great width of the frame throughout its full height, or the grab is in any other way given a shape that makes it less suited for working in hatchways or the like, because projecting parts of the grab may seize the coaming. The present invention has for its purpose to improve grabs of the kind referred to by making it possible to insure by simple means and without the use of guiding rails that the jaws of the grab assume always during the opening and closing of the grab symmetrical positions relatively to the vertical axis of the grab. The invention also has for its object to so shape the bucket grab that it tapers upwards and has no projecting parts which might seize a hatchway or the like. The invention also relates to a particular connection between the lower part of the frame and its struts so as to increase the closing force of the grab and facilitate at the same time its opening and make its construction cheaper. The invention will be described with reference to the drawing but is not limited to the embodiments shown therein, as it comprises any construction falling within the scope of the appended claims. Similar reference characters in the drawing refer to similar parts. Fig. 1 shows diagrammatically an embodiment of the invention in elevation and with the movable parts shown in their closed position in full lines and in their open position in broken lines. Fig. 2 shows on a larger scale the guiding of the closing crosshead of the embodiment in Fig. 1. Figs. 3 and 4 show other embodiments of the guiding of the closing cross-head. Fig. 5 shows an embodiment in which the broken lines indicate, as in Fig. 1, the open position of the grab, and the full lines indicate the closed position thereof, whereby the guiding of the closing crosshead corresponds chiefly to that shown in Fig. 1, while the frame is constructed with linked connections. Fig. 6 is a front view of the embodiment shown in Fig. 5 and with the movable parts shown in the closed position of the grab, and Fig. 7 an other modification of the guiding of the closing crosshead. In Fig. 1, 1 is a frame to which the jaws 3 of the grab are pivoted by pivots 2. 4, 4 are closing cables running over pulleys 5 mounted in a closing crosshead 6 and other pulleys 7 mounted in the top piece 8 of the frame. 9 is an opening cable secured to the said top piece. The upper parts of the jaws, when in closed position, are provided or formed with toothed arcs 10, as shown in Fig. 2. 11, 11 are other toothed arcs on links 12 connecting the jaws 3 with the crosshead 6 by means of pivots 13, 14 passing through the centres of the arcs 10, 11. The arcs 11 mesh with each other, while the arcs 10 mesh with gear wheels 15 mounted on the pivots 14 and meshing with each other. The rectilinear guiding of the closing crosshead 6 is obtained by the arcs 10, gear wheels 15 and the arcs 11 of links 12, the way in which these elements mesh with each other preventing the crosshead from making any lateral and rotary motions which it would be able to make relative to the pivots 2, 13, 14, if the crosshead were connected with the jaws only by links 12. In the embodiment shown in Fig. 3 the cross-head 6 is pro-

vided with a guideway 16, in which slides a block 17 carrying a pin 18. On said pin are mounted two links 19, each of which is connected with one of the jaws 3 by a pivot 5 20 so placed that its axis does not coincide with the axis of the pivot 13. As in Fig. 1, the links 12 are provided with toothed sectors 11 meshing with each other. In Fig. 4 is shown an embodiment corresponding essentially to Fig. 3, the guide 16 being, however replaced by a two-armed lever 22 pivoted on a stationary pivot 21, the links 19 being secured to the ends of said lever 22. By this arrangement, the use of arcs 11 on the links 15 20 is not strictly necessary. A lateral motion or turning of the closing crosshead is prevented by the links 19 and 12, which together cause a rectilinear guiding of the closing crosshead, from which results again a symmetrical motion of the jaws during their opening and closing operations. By the grab shown in Fig. 5 the guiding differs from that of Fig. 1 in this that between the toothed arcs 10 and gear wheels 15 are provided 25 intermediate gear wheels 23 mounted on pivots 24 in the links 12, whereby advantage is obtained mainly that the said arcs 10 and gear wheels 15 may be reduced in size. The frame is constructed with link connections, 30 its lower horizontal part 25, on which the pivots 2 of the jaws are placed, being not directly connected with the struts 26 of the frame, which are instead thereof connected with the jaws by pivots 27 placed oppositely to pivots 13 in relation to a vertical plane through pivots 2, while at their top they are connected with the top piece 8 by pivots 28 and guided in a well-known manner relative to each other by meshing. Thereby, in 35 the first place a greater gripping force is obtained, as the pressure in the struts 26 during the closing of the grab gives a moment relative to the pivots 2, which are in this case to be considered as the stationary axes of 40 rotation of the jaws, the said moment acting to close the grab, and secondly an easier opening of the grab, the weight of the jaws and of the horizontal part 25 of the frame affording during the opening a great moment relative to the pivots 27, this moment acting to 45 open the grab. Moreover a longer way is obtained for the force in the closing cables, since to the way of the closing crosshead must be added the way covered by the top piece 50 during the opening because of the link connections. The top piece is prevented in a well-known way from lateral or turning movements for example by providing the top ends of the struts with intermeshing teeth. 55 Finally, the advantage is obtained by the use of links in a frame with stationary pivot points for the jaws, instead of the old constructions having rigid frames of the same kind, in that the difficult rivetings corresponding to the great forces in question are

avoided and the parts of the frame may simply be carried out as tension and compression members without bending strains. Fig. 6 shows that the grab, as seen from the front, has a smooth shape tapering upwardly, the elements necessary to the guiding of the closing crosshead projecting nowhere outside of the struts of the frame. Moreover it will be seen from Figs. 1, 5 and 6 that according to the invention the right 70 and left jaw of the grab may be made completely alike. The height of the grab is very small in proportion to the wide opening, whereby amongst other advantages an increased stability is obtained. The embodiment shown in Fig. 7 is distinguished by a particularly simple construction. The closing crosshead 6 carries a plate 29 provided with slots 30 in which slide pins 31 on the jaws 3, when the grab is opened and closed. 75 As the pins 31 can be moved only in the paths fixed by the slots, it is understood that a proper guiding of the closing crosshead and jaws can be obtained. Instead of slots 30 being provided in the plate 29 a plate or 80 plates can be used having cam edges cooperating with the pins 31, which cam edges are of such a shape, that the desired guiding operation is obtained. In the drawing the links 12 are provided with toothed arcs 11 and 85 journaled at 14. However the links 12 can also be pivoted by a common pivot, in which case the toothed arcs 11 will be dispensed with. Instead of a pulley connection, or the like, between the closing crosshead and the 90 top piece of the grab the necessary closing force may be obtained in any other well-known manner, for example by means of a differential pulley or by an electric motor arranged in the grab in combination with 95 suitable gearing.

I claim:

1. A grab comprising a frame, jaws having their axes of rotation fixed in said frame relative to each other, a closing crosshead, pivotally links connecting said crosshead with the uppermost portions of said jaws, and means for vertically guiding said closing crosshead relative to said frame and said jaws, said means comprising intermeshing toothed arcs 115 on said links, toothed arcs on the jaws, and intermeshing gear wheels mounted on the pivots connecting said links with said closing crosshead and coacting with said last named arcs.

2. A grab comprising a frame, jaws having their axes of rotation fixed in said frame relative to each other, a closing crosshead, links connecting said crosshead with the uppermost portions of said jaws, and other links connecting said jaws indirectly with said closing crosshead.

3. A grab comprising a frame, jaws having their axes of rotation fixed in the frame relative to each other, a closing crosshead, and

means for vertically guiding the crosshead comprising links connecting said crosshead with the uppermost portions of said jaws, pins carried by the jaws, and plates carried by the crosshead and having cam formations cooperating with said pins.

4. A grab comprising a frame, jaws pivoted at relatively fixed points to said frame, a closing crosshead, and connections between the jaws and the crosshead, entirely independent of any connection of either the jaws or the crosshead with the frame, to hold the vertical axis of the crosshead coincident with the vertical axis of symmetry of the jaws during opening and closing movements of the jaws.

5. A grab comprising a frame, jaws pivoted at relatively fixed points to said frame, a closing crosshead, and means comprising connections solely between the jaws and the crosshead to hold the vertical axis of the crosshead coincident with the vertical axis of symmetry of the jaws during opening and closing movements of the jaws.

6. A grab comprising a frame, jaws pivoted at relatively fixed points to said frame, a closing crosshead, and means comprising link and cooperating gear connections solely between the jaws and the crosshead to hold the vertical axis of the crosshead coincident with the vertical axis of symmetry of the jaws during opening and closing movements of the jaws.

7. A grab comprising a frame, jaws pivoted at relatively fixed points to said frame, a closing crosshead, links pivotally connected at adjacent ends to the crosshead and at their outer ends pivotally connected to the jaws, and other connections solely between the jaws and the crosshead cooperating with said links to hold the vertical axis of the crosshead coincident with the vertical axis of symmetry of the jaws during opening and closing movements of the jaws.

8. A grab comprising a frame inclusive of a bottom part and struts separate therefrom, jaws having spaced pivotal connections with the bottom part and said struts, respectively, a closing crosshead, and means entirely independent of any connection of either the jaws or the crosshead with the frame for vertically guiding the crosshead during opening and closing movements of the jaws, said means comprising links pivotally connecting the crosshead with the jaws, and cooperating gear connections between the jaws and the crosshead.

In testimony whereof I affix my signature.
EJGIL VALDEMAR PETERSEN DYGGVE.
